EMERGENCY EXIT WINDOW STRUCTURE

Roy Stouder, Goshen, and Harvey Carbiener and David L. Rutter, Elkhart, Ind., assignors to Excel Corporation, Elkhart, Ind., a corporation of Indiana

Application November 24, 1953, Serial No. 394,034

10 Claims. (Cl. 189—64)

This invention relates to emergency exit window structure, and has particular reference to an improved means for releasably securing a push-out type of emergency exit sash in a vehicle window opening.

As is well-known, busses, railway cars and similar public conveyances are frequently equipped with emergency exit windows wherein the window sash can be quickly removed from the window opening to provide an exit for trapped passengers in the event of an accident. Many types of emergency sash are normally retained in place by fastening means which must first be released by operating a lever or button before the sash can be removed from, or swung out in, the window opening. Other types, such as those commonly known as push-out or knock-out sash, may be removed by simply applying sufficient force to the sash itself, which force overcomes the holding action of the fastening means and pushes the sash out in a single operation. This latter type of sash is gaining increasing favor with safety authorities and also with vehicle manufacturers for the obvious reason that its emergency operation is quicker and more certain, and in many jurisdictions it is now specified that the emergency exit windows in school busses must be provided with sash of the push-out type.

While the push-out or knock-out type sash has proved satisfactory in most respects, and has the advantage of very fast emergency operation, certain disadvantages have been noted in conjunction with the various fastening means heretofore employed to retain the sash in normal, window closing position. Thus, in many arrangements, the fastening means include expendable parts which are destroyed or lost whenever the sash is intentionally or accidentally pushed out. This, of course, necessitates replacement parts and frequently means that the vehicle must be sent to the repair garage in order to properly re-secure the sash in window closing position. In other arrangements, even though none of the fastening elements are destroyed or lost, the vehicle must still be sent to the garage to have the sash restored to window closing position. A few arrangements avoid the above-noted disadvantages but in so doing usually introduce more complex and expensive sash and fastening structure. While these disadvantages have been noted in passenger vehicles of all types, they are of particular concern in the case of school busses where the emergency exit sash are sometimes accidentally pushed out by overly rambunctious students and the inconvenience and expense of properly re-securing the sash after each such occurrence can become appreciable.

With the foregoing and other considerations in view, it is the primary object of the present invention to provide an improved fastening means for releasably securing a push-out type sash in an emergency exit window, which fastening means has no expendable parts and yet is simple and economical to use. The fastening arrangement provided is particularly well adapted for use in school busses although it can be utilized with improved results in commercial passenger carrying vehicles as well.

A more specific object of the invention is to provide an improved push-out sash fastening means which may be quickly and easily reassembled by the vehicle operator to restore the sash to window closing position after it has been intentionally or accidentally pushed out.

Another specific object of the invention is to provide an improved push-out sash fastening means which normally retains the sash in tightly sealed, rattle-proof relation to the window frame.

2

A further specific object of the invention is to provide an improved push-out sash fastening means which is substantially tamper-proof.

Another object of the invention is to provide a push-out sash comprising normally operated fixed and movable sub-sash or panels.

Still another object of the invention is to provide a push-out sash comprising fixed and movable sub-sash which can be swingably mounted as a unit in a window opening.

A further object of the invention is to provide an emergency exit window construction having a push-out type sash which construction has good sealing characteristics between the window frame and sash, and yet which eliminates edge sealing and the possible necessity for resealing after the sash has been pushed out.

A still further object of the invention is to provide an emergency exit window construction which is economical to manufacture, install and maintain.

Other objects and advantages will become apparent from the following detailed description read in conjunction with the accompanying drawings, wherein like reference numbers designate corresponding parts in all the views.

25 In the drawings:

Figure 1 is a side elevation of an emergency exit window construction embodying the invention, the elevation being taken from inside the vehicle.

Figure 2 is an enlarged vertical section taken on the line 2—2 of Figure 1;

Figure 3 is a fragmentary horizontal section on the line 3—3 of Figure 1;

Figure 4 is a fragmentary vertical section taken on the line 4—4 of Figure 3;

35 Figures 5 and 6 are fragmentary horizontal sections taken respectively on lines 5—5 and 6—6 of Figure 1;

Figure 7 is a fragmentary vertical section taken on line 7—7 of Figure 1 showing one form of the improved push-out sash fastening means of the invention;

40 Figure 8 is a fragmentary vertical section corresponding to the section of Figure 7 and showing another form of the improved push-out sash fastening means of the invention; and

Figure 9 is an enlarged plan view of the head of one of the screws employed in the invention.

Having reference now to the drawings, which illustrate a typical embodiment of the invention for the purpose of disclosure, 10 generally indicates a push-out sash mounted in a window frame 11 formed by the body panels of the vehicle.

50 The push-out sash 10 comprises side rails or stiles 12, a top rail or header 14 and upper and lower sub-sash or panels 15, 17, the upper panel being movable and the lower panel fixed as is typical in sash construction for school busses. The stiles 12 are of the double channel type, open at both ends, and each is formed of an angle bar 18 and a channel bar 20, Figures 5 and 6, secured together as by welding to provide inner and outer vertical channels 21, 22, respectively. The header 14, Figure 2, is also of channel conformation, from the same stock as bars 20, and is secured between the upper ends of the latter so that its channel 24 communicates with outer vertical channels 22. As may be best seen in Figures 1 and 3, bars 20 are provided with upper end extensions 25 which are folded over the top of the header to give greater rigidity to the sash frame.

65 Upper and lower panels 15, 17 are substantially conventional double glazed sash, lower panel 17 comprising laminated sheet glass 26, sash glazing rubber 27 and a supporting frame having a bottom rail 28, stiles 30, 31 integrally connected thereto, and a removable top rail 32 to permit access to the glass. Stiles 30, 31 are formed with guide ribs 34, Figure 6, which are received in weatherstripping 35 mounted in the inner channels 21 of the sash frame stiles 12. As noted hereinabove, lower panel 17 is fixed and is rigidly secured to the sash frame as by screws 37, Figure 1, which pass through the frame stiles 12 and panel ribs 34. In this manner, panel 17 completes the lower portion of the sash frame and its bottom rail 28 serves also as the bottom rail for said frame.

Upper panel 15 is similar in construction to lower panel 17 and comprises laminated sheet glass 38, sash glazing rubber 40 and a frame having a bottom rail 41, stiles 42, 44 and a top rail 45. Stiles 42, 44 and top rail 45 are formed with guide ribs 47, Figures 2 and 3, which are received in weatherstripping 48 mounted in the outer channels 22 and channel 24 of the sash frame, stiles and header, respectively. Panel 15 is a movable, drop type sash guided by the channels 22 and is maintained in any given position by sash locks 50 (only one of which is shown in Figure 1) which coat in a well-known manner with stops 51 formed in the upper portion of inner channels 21.

The push-out sash 10 is swingably mounted in the window frame 11 by means of a pair of double action hinges 52, Figures 2-4, extending between the body panels 54 forming the sides of the window frame and the stiles 12 of the sash frame adjacent the top rail or header 14 thereof. Each hinge comprises an offset plate 55 pivotally secured at 57 to the panel 54 and at 58 to the stile 12, a slot 60 being cut in the side wall of the channel bar 20 of the stile to permit the plate to extend therethrough. Double action hinges are provided so that the push-out sash 10 may be swung outwardly 90° in the frame in spite of the overhanging drip cap 61, Figure 4. Thus, when the sash is first pushed outwardly, it pivots about pivot point 58 until the bottom rail 28 clears the sill 62 of the window frame; thereafter, the hinge plate 55 pivots about pivot point 57 while the sash continues to pivot about point 58 which permits the sash to be fully opened and yet clear the drip cap. It will be understood, of course, that in vehicle constructions which do not employ a drip cap, or where the cap does not overhang the window frame, a conventional type of leaf or piano hinge may be used to pivotally secure the top rail 14 of the sash to the body panel 64 forming the top of the window frame.

The window frame 11 is formed with an upstanding flange 65 at the inner side thereof adjacent the bottom rail 28 of the push-out sash. A strip of resilient weatherstripping 67 is bonded or otherwise secured to the flange, and the rail bears against this weatherstripping when the sash is in closed position. The sash is releasably secured in window closing position by fastening means which include a plurality of oversized apertures 68, Figure 7, formed in the flange 65 and weatherstripping 67, and a plurality of shouldered screws 70 corresponding to the apertures and threaded into the bottom rail 28. The heads 71 of the screws are of smaller diameter than the diameter of the apertures but are normally prevented from passing therethrough by means of resilient grommets 72 of some suitable material such as rubber, the grommets being of larger diameter than the diameter of the apertures and positioned on the screws between the heads thereof and the inner surface of the flange as shown. The fastening means just described normally holds the sash 10 securely in window closing position, but when the sash must be opened and sufficient outward force is applied thereto the heads 71 of the screws force the portions 74 of the grommets abutting the heads into the annular spaces 75 between the shanks of the screws and the edges of the oversized apertures permitting the screw heads to pass through the apertures and the sash to swing free. In this manner, the screws 70 remain with the sash while the grommets remain stuck to the flange or else drop down inside the bus where they can be easily recovered. In re-securing the sash, it is necessary only to remove the screws from the rail 28, re-position the grommets on the screws, and re-thread the latter into the rail with the grommets bearing against the flange as before. The amount of pressure needed to push the sash out can be regulated by the thickness of the grommets through which the screw heads must pass. Thus, the thicker the grommets, the greater the pressure needed, and vice versa. Grommets 72 are moulded into metallic cups 77 to prevent students or other passengers from cutting or otherwise destroying them. The screw heads 71, Figure 9, are of a special type having portions 78 thereof scooped out on opposite sides of the slot 79, as shown, whereby the screws may be tightened with a screw driver but can not be backed out by a screw driver, knife, coin or the like since the instrument will climb up and out of the slot.

Figure 8 illustrates a modified form of grommet comprising a cylindrical body 80 having a diameter that is

substantially equal to the diameter of the apertures 68 and a flange 81 integral with the body 80 and having a larger diameter than that of the apertures. These grommets are positioned on the screws 70 so that when the latter are threaded into the bottom rail 28 of the sash the cylindrical portions of the grommets are positioned in the apertures while the flanges 81 thereof bear against the flange 65 to retain the sash in window closing position. In this modified form, when sufficient outward force is applied to the sash, the flanges 81 of the grommets are rolled over the heads of the screws, as indicated by the dash line, and both the grommets and screws are pushed through the apertures to allow the sash to swing free. In re-securing the sash, the screws and grommets are simply removed from the rail and then reassembled therewith from the inside of the flange 65. With either of the forms of grommet described, there are no expendable parts and when the sash is accidentally pushed out, as sometimes happens in school busses, the operator of the bus can easily restore the sash to proper window closing position using an ordinary screw driver.

Window frame 11 is formed with vertical inside flanges 32 which are continuations of the upstanding flange 65 and these flanges carry weatherstripping 84 against which the stiles 12 of the push-out sash 10 bear when the latter is in closed position. Similarly, the top rail 14 of the sash bears against weatherstripping 85 carried by the body panel 64 forming the top of the window frame. In this manner, the push-out sash is held in sealed and rat-tle proof relation to the window frame without edge sealing and the possible necessity for resealing after the sash has been pushed out. The push-out sash can be assembled as a unit in the window frame by simply securing the two hinge plates 55 to the panels 54 by shoulder screws 57, and securing the bottom of the sash in position by means of the shouldered screws 70 and grommets 72, three sets of such screws and grommets being adequate for an average sized sash as shown.

From the foregoing description it will be apparent that the subject invention provides a simplified and yet highly efficient emergency exit window construction including a greatly improved releasable fastening means for a push-out type sash. The invention may be embodied in other specific forms without departing from the spirit or essential characteristics thereof. The embodiments disclosed are therefore to be considered in all respects as illustrative rather than restrictive, the scope of the invention being indicated by the appended claims.

What we claim is:

1. In an emergency exit window structure having a pushout sash swingably mounted adjacent one rail in a window opening, releasable fastening means to normally maintain said sash in window closing position comprising a fixed member adjacent the opposite rail of said sash having an aperture therethrough, a screw threaded into said opposite rail, the shank and head of said screw extending through said aperture, the aperture being of larger diameter than the diameter of the screw head, and a resilient grommet element of larger diameter than the diameter of said aperture positioned between the screw head and said fixed member.
2. Releasable fastening means for a push-out sash swingably mounted adjacent one longitudinal rail in a window frame comprising a flange on said window frame adjacent the opposite longitudinal rail of said sash and having an aperture therethrough, a screw threaded into said opposite rail, the shank and head of said screw extending through said aperture, the latter being of larger diameter than the diameter of the screw head, and a resilient grommet element of larger over-all diameter than the diameter of said aperture positioned between the screw head and said flange.
3. In combination with a push-out sash swingably mounted adjacent its top rail in a window frame, releasable fastening means to normally maintain said sash in window closing position comprising a flange on said window frame adjacent the bottom rail of said sash and having a plurality of circular apertures therein, a plurality of shouldered screws threaded into said bottom rail, the shank and head of each screw extending through one of said apertures, said apertures being of larger diameter than the diameter of the screw heads, and a resilient grommet of larger over-all diameter than the diameter of said apertures positioned on each screw, at least a portion

of said grommet being positioned between the screw head and said flange.

4. Releasable fastening means for a push-out sash swingably mounted adjacent one longitudinal rail in a window frame comprising a flange on said window frame adjacent the opposite longitudinal rail of said sash and having an aperture therethrough, a screw threaded into said opposite rail and extending through said aperture, the aperture being of larger diameter than the diameter of the screw head, and resilient means to normally secure said screw in said aperture, said means being operable to permit said screw to pass out of said aperture upon the application of sufficient force to said sash.

5. Emergency exit window structure for vehicles comprising a window frame formed by the body members of the vehicle, a drip cap mounted on the outside of said frame and overhanging the upper edge thereof, a push-out sash, double action hinge means to pivotally mount the top rail of said sash in said frame, said hinge means permitting said sash to swing outwardly 90° in said frame and clear said drip cap, a flange on said frame adjacent the bottom rail of said sash and having an aperture therethrough, a screw threaded into said bottom rail and extending through said aperture, the aperture being of larger diameter than the diameter of the screw head, and resilient means engaging said screw and flange to normally retain the former in said aperture and hold said sash in window closing position, said means being operable upon the application of sufficient force to said sash to release said screw from said aperture and permit the sash to swing outwardly in said frame.

6. In combination with a push-out sash swingably mounted adjacent its top rail in a window frame, releas-

able fastening means to normally maintain said sash in window closing position comprising a flange on said window frame adjacent the bottom rail of said sash and having a plurality of circular apertures therein, a plurality of shouldered screws threaded into said bottom rail, the shank and head of each screw extending through one of said apertures, said apertures being of larger diameter than the diameter of the screw heads, and a resilient grommet of larger over-all diameter than the diameter of said apertures positioned against the head of each screw and engaging said flange to secure the screws and lower sash rail to the flange, said grommets being distortable to permit said screws to be disengaged from said flange upon the application of sufficient force to the sash.

7. Structure as defined in claim 6 wherein said grommets are formed of rubber.

8. Structure as defined in claim 6 wherein each of said grommets comprises a cylindrical body having a diameter substantially equal to the diameter of said apertures, and a flange integral with said body having a diameter larger than that of the apertures.

9. Structure as defined in claim 6 wherein each of said grommets comprises a substantially discoidal body of larger diameter than the diameter of said apertures.

10. Structure as defined in claim 9 wherein each of said grommets is moulded into a rigid, substantially cup-shaped element.
